United States Patent Office

Des. 186,885
Patented Dec. 22, 1959

186,885

BRASSIERE OR THE LIKE

Herbert Barg, Merion, Pa., assignor to True Form Foundations, Inc., Darby, Pa., a corporation of Pennsylvania

Application June 8, 1959, Serial No. 56,267

Term of patent 14 years

(Cl. D20—4)

FIG. 1.

FIG. 2.

Fig. 1 is a front perspective view of a brassiere showing my new design; and

Fig. 2 is a rear perspective view of the brassiere of Fig. 1.

I claim:

The ornamental design for a brassiere or the like, as shown.
